PULL KNOB

George D. Read, Glendora, Lawrence Glen McCain,
Beverly Hills, and Edward William Scott, Culver City,
Calif., assignors to Ajax Hardware Corporation, City
of Industry, Calif.

Filed Oct. 15, 1974, Ser. No. 514,821

Term of patent 14 years

Int. Cl. D8—06

U.S. Cl. D8—143

FIG. 1 is a front view of our pull knob;
FIG. 2 is a side view of our pull knob;
FIG. 3 is a top view of our pull knob;
FIG. 4 is a rear view of our pull knob; and
FIG. 5 is a view taken along the line 5—5 of FIG. 1.
We claim:
The ornamental design for a pull knob, as shown.
